CLAIM

The ornamental design for a takeup module housing, as shown and described.

DESCRIPTION

This application is related to U.S. Utility application Ser. No. 14/543,794, now U.S. Pat. No. 9,708,154, issued Jul. 18, 2017 and titled “OFF-ROAD ROLLING FILM VISION SYSTEM”. This application is related to Design patent applications Ser. No. 29/509,397 titled “FILM SPOOL;” Ser. No. 29/509,401 titled “ROLLOUT MODULE HOUSING;” and Ser. No. 29/509,403 titled “CONTROLLER HOUSING;” all filed Nov. 17, 2014; and to U.S. Utility application Ser. No. 14/967,150 filed Dec. 11, 2015, and to U.S. Utility application Ser. No. 15/650,864 filed Jul. 15, 2017, and to PCT/US2015/56987 filed Oct. 22, 2015. All applications have the same inventor and owner.

FIG. 1 is a top view of a takeup module housing, showing my new design;

FIG. 2 is a bottom view thereof;

FIG. 3 is a back view thereof;

FIG. 4 is a front view thereof;

FIG. 5 is left side view thereof;

FIG. 6 is right side view thereof; and,

FIG. 7 is back perspective view thereof.

The broken lines depict portions of a takeup module housing in which the design is embodied that form no part of the claimed design.
